UNITED STATES PATENT OFFICE.

EWALD MUNDT, OF NEW YORK, N. Y., ASSIGNOR TO WILLIAM MUNDT, OF SAME PLACE.

SPOOL-HOLDER FOR BRAIDING-MACHINES.

SPECIFICATION forming part of Letters Patent No. 632,534, dated September 5, 1899.

Application filed January 30, 1899. Serial No. 703,789. (No model.)

To all whom it may concern:

Be it known that I, EWALD MUNDT, a citizen of the United States, residing at New York, in the borough of Manhattan and State 5 of New York, have invented certain new and useful Improvements in Spool-Holders for Braiding-Machines, of which the following is a specification.

This invention relates to certain improvements in spool-holders for braiding-machines, by which the friction of the thread along the bobbin in unwinding is obviated and the sliding up of the spool on the spindle prevented, so that for these reasons the size of the spool 15 can be considerably enlarged and a greater quantity of thread wound on the same.

The invention consists of a spool-holder for braiding-machines comprising a standard having a tension-eye, a spindle, a spool on 20 the latter, an arcuate guard-plate spanning the periphery of the spool from a point adjacent to the tension-eye, said guard-plate having an outer thread-guiding surface, a leading-on edge and a leading-off edge, and means 25 against which the upper end of the guard-plate abuts, all as will be hereinafter particularly described in detail and then pointed out in the claims.

In the accompanying drawings, Figure 1 30 represents a side elevation of my improved spool-holder for braiding-machines. Fig. 2 is a horizontal section on line 2 2, Fig. 1. Fig. 3 is a side elevation of the upper part of the spool-holder, partly in section, through 35 the locking-latch of the same, drawn on a larger scale. Fig. 4 is a plan view of Fig. 3, and Fig. 5 is a perspective view of the latch shown as removed from the spool-holder.

Similar letters of reference indicate corresponding parts.

Referring to the drawings, A represents a spool on which the braid-forming thread is wound, and C a spindle which is mounted on a base F, that is provided with top and bottom plates F' F² and a vertical plate F³ between the same, which plates serve to guide the spool-holder in the serpentine grooves in the base-plate of the braiding-machine. To the top plate F' is attached the upright standard B, which serves as a guide for the tension-weight B' of the thread.

On the lower part of the spindle C is placed a disk D, which serves as the support for the spool A. The disk D is provided with a sleeve d, that rests on the base F. Around the 55 spool and concentric with the spindle is arranged an arcuate guard-plate G, which is attached to the disk D and which is made of suitable sheet metal.

The upper end of the spool A is provided 60 with teeth a, which are engaged by a pawl p, that slides freely on the upper part of the standard B whenever it is lifted by the upward motion of the tension-weight, so as to intermittently remove the same from the 65 teeth of the spool and permit the turning of the latter and the supply of thread to the braid made on the machine. The thread is led from the spool over the leading-on edge of the guard-plate G and around and upon 70 its outer surface, from whence it passes off of the leading-off edge located nearest to a hole o in standard B, through said hole o, then through the tension-eye b' of the weight B', and lastly through the tension-eye e in the 75 locking-latch E at the upper end of the standard B. The guard-plate G has a broad surface, so that the leading-on edge is located at a considerable distance from the leading-off edge, thereby enabling it to span quite a 80 portion of the periphery of the spool.

The locking-latch E is clearly shown in Figs. 3, 4, and 5, and consists of an angular plate that is locked at about its middle by means of a slot e' therein, said latch at one end of 85 said slot entering a recess e^x in the upper end of spindle C, while a projecting heel e² at its angle fits into a recess e³ of the standard B and the centrally-recessed upper end of the latter into side recesses e⁴ of its eye-carrying 90 end, its other end abutting against the inner surface of the guard-plate G. The locking-latch connects the standard B, spindle C, and guard-plate G, and holds the spindle rigidly in position, while it forms an abutment or support for the upper end of the guard-plate. 95

By arranging the guard-plate concentrically around the spool and conducting the thread around the same the vertical sliding motion of the spool on the spindle is entirely 100 dispensed with and the spool enabled to follow freely the motion of the thread as it un-

winds upward or downward from the spool without exerting any friction on the bobbin, the guard-plate neutralizing the friction to which the thread was heretofore subjected in 5 unwinding from the spool. The spool is therefore not liable to slide upon the spindle under the tension of the thread and can therefore be made longer in size, so as to permit the winding of a much greater quantity of 10 thread on the same, while the easy and almost frictionless motion of the spool is produced. As the locking-latch can be readily detached from the standard and spindle on pressing the upper end of the spindle side- 15 wise in the slot e' , the empty spool can be readily removed from the spindle and replaced by a full spool when the latch is replaced into position for locking the parts together.

20 Having thus described my invention, I claim as new and desire to secure by Letters Patent—

25 1. A spool-holder for braiding-machines, comprising a standard having a tension-eye, a spindle, a spool on the latter, an arcuate guard-plate, spanning the periphery of the spool from a point adjacent to the tension-eye, said guard-plate having an outer thread-guiding surface, a leading-on edge and a leading-off edge, and means against which the upper end of the guard-plate abuts, substantially as set forth.

30 2. A spool-holder for braiding-machines, comprising a standard having a tension-eye, a spindle, a disk on said spindle, a spool on the latter, an arcuate guard-plate rising from

said disk, and spanning the periphery of the spool from a point adjacent to the tension-eye, said guard-plate having an outer thread-guiding surface, a leading-on edge and a leading-off edge, and means supported at the upper end of said spindle, against which the upper end of said guard-plate abuts, substantially as set forth. 40

3. In a spool-holder for braiding-machines, 45 the combination of a standard, a spool-spindle, a guard-plate located on the opposite side of the spindle from the standard, and a locking-latch interlocking with the upper ends of the spindle and standard, said guard-plate 50 abutting against the end of said latch, substantially as set forth.

4. In a spool-holder for braiding-machines, the combination of a standard, a spindle, having a recessed upper end, a disk on said spindle, a spool supported on said disk, a guard-plate attached to said disk and extending around the spool, and an angular locking-latch, connecting the upper ends of the standard and spindle, said locking-latch having a 55 side recess and a projecting heel interlocking with the standard and a slot interlocking with the recessed upper end of the spindle, substantially as set forth.

In testimony that I claim the foregoing as 60 my invention I have signed my name in presence of two subscribing witnesses.

EWALD MUNDT.
